UNITED STATES PATENT OFFICE.

WILLIAM N. PARKES, OF BROOKLYN, NEW YORK, ASSIGNOR TO THE PARKES MACHINE COMPANY, OF NEW YORK, N. Y., A CORPORATION OF NEW YORK.

STITCH-FORMING MECHANISM FOR SEWING-MACHINES.

1,119,865.

Specification of Letters Patent.

Patented Dec. 8, 1914.

Application filed February 7, 1902. Serial No. 93,037.

To all whom it may concern:

Be it known that I, WILLIAM N. PARKES, citizen of the United States, and resident of Brooklyn, in the county of Kings and State of New York, have invented certain new and useful Improvements in Stitch-Forming Mechanism for Sewing-Machines, of which the following is a specification.

This invention relates to the lock stitch class of sewing machines, which comprises a revolving bobbin case carrying looper, the loop engaging position of which is not changed laterally, and a reciprocating needle, the loop engaging position of which is changed laterally.

In my machine the hook or looper is revolved a plurality of times, or twice to each vertical thrust of a lateral moving needle. Machines of the prior art having these relative movements between the needle and the hook are not adapted for general work.

One of the main objects of my invention is to construct a stitch forming mechanism in which the needle and hook have the relative movements mentioned, that is adapted for general use, and not therefore limited to specific use as are the machines of this class in the prior art in which the said relative movements between the needle and the hook are used.

Generally speaking the object of my present invention is a part of a general object shown and described in my various patents, namely the construction of an improved stitch forming mechanism for use in the various machines I have invented, in which the loop engaging position of the needle is changed laterally. And it is also an object of my invention to adapt a stitch forming mechanism having the relative movements mentioned between the needle and the hook, for use in other special and general stitching machines.

I have not shown in my present application a feeding mechanism, but I have shown my invention located and adapted so a feeding or work moving mechanism may be used in combination with it. And I have shown such mechanism in use in combination with my present invention in my U. S. Patents Nos. 875,611-875,613-875,616 and 875,623 issued to me December 31, 1907. From these patents the important object of locating the revolving hook of my stitch forming mechanism below the needle or cloth plate, and

back of the path of the needle will be obvious, and applicant desires to emphasize this important feature of his invention.

By referring to U. S. Patents Nos. 875,624-875,626 and 875,628 issued to applicant December 31, 1907, a further important object of the relative location of parts mentioned will be understood. One of the important functions secured by this relative location of parts, is, the adaptation of a stitch forming mechanism, the hook of which is revolved a plurality of times to each thrust of a laterally moving needle, for use in machines in which it is necessary to have the hook located below the work, and back of the path of the needle, and this is one of the main characteristics of my present invention.

Referring to the drawings, Figure 1 is a front elevation of a machine embodying my invention, parts being broken away, or partly in section, to disclose details of the mechanism; Fig. 2 is a front end view, the face plate being removed to disclose the needle bar operating mechanism and parts of the machine being removed, or partly in section, to disclose details of construction; Fig. 3 is a view of the needle bar showing the relative position of the parts in connection with the same when the needles are in one of their lateral positions; Fig. 4 is a view of the same when the needles are in the other of their lateral positions; Fig. 5 is a side view of the said needle bar and operating parts in connection with the same; Fig. 6 is a detail showing parts of the connection between the segment lever F and the swinging arm which oscillates the needle bar; Fig. 7 is a detail partly in section of the same showing the construction thereof; and Fig. 8 is a detail view of the cam part of collar 11.

In the drawings, A represents the overhanging arm, B the bed plate, C the presser bar, D the lower shaft, E the upper shaft, F the segment lever, and G a switch cam attached to the upper shaft E, which is adapted to operate the said segment lever, all of which are of a usual construction and are operated in a usual manner.

To the forward end of the shaft E is connected a disk 1 to which the crank pin 2 is suitably attached, and on the said crank pin is pivoted the upper end of a link 3. A tubular needle bar 4 is suitably guided to be

reciprocated and axially oscillated in the bearings 5 and 6, and to the needle bar are attached cam parts or collars 7 and 8 which encircle the said needle bar, are adjustable thereon and secured thereto by means of screws 9 and 10. On the said cam parts or collars are formed respectively cam surfaces 14 and 15.

The needle bar passes through a cam part 19 or collar 11 having cam surfaces 12 and 13 formed thereon, which are adapted to engage respectively the said cam surfaces 15 and 14, as shown in Figs. 2, 3, 4 and 5. On the cam part or collar 11 is formed a round extension or lug 11^a which is located in a hole formed in the lower end of the aforesaid link 3, the said end of the said link being extended laterally so as to form a substantial bearing for the said lug 11^a of the collar 11, and the upper end of the said link 3 being also extended to form a substantial bearing for the said crank pin 2, as shown in Fig. 5. These cam surfaces serve to vary the thrust of the needle to compensate for the vertical movement of the needle during the time the beak of the looper is moving from a first to a second position of loop engagement, and thereby maintain vertically the relation between the eye of the needle and the beak of the looper, which permits a lateral movement of a greater extent being given the needle. These cam surfaces are so constructed that when the needle is moved laterally in the same direction in which the looper revolves the position of the needle is changed downwardly, and vice versa when the needle is moved in the opposite direction.

To the lower end of the needle bar 4 is suitably secured a needle clamp 19 in which the needles 20 and 21 are clamped by means of clamping screws 22 and 23. On the said clamp is formed a projection 24 through which holes 25 and 26 are formed to lead the thread to the needles. The needles 20 and 21 are provided with the usual thread eyes 20^a and 21^a which run through the needle at right angles to the direction in which they are moved laterally. It is obvious, of course, that one of these needles may be omitted from the machine when the work of only one needle is desired.

To the needle bar 4 is attached, by means of a set screw 16, an arm 17 which has a vertically extending rod 18 secured to it, as shown in Fig. 2. A bearing 27 is attached to the forward end of the arm A of the machine, as shown in Figs. 1 and 2. On the said bearings is pivoted an arm or lever 28 having a downwardly extending part 29 through which is formed a vertical bore in which the upwardly extending rod 18 is adapted to reciprocate. A collar 30 suitably connected to the upper end of the bearing 27 serves as a means for retaining the arm

28 on the said bearing. By means of a ball joint connection, one end of a link 31 is connected to the part 29 of the arm 28. The other end of the said link passes through an enlarged end 33 of a threaded bolt 32. The said bolt 32 passes through one end of a connecting part 35, a socket 34 being formed in the said connecting part 35 for the reception of the said enlarged end 33. A channel 36 is formed longitudinally in the said connecting part 35 for locating and guiding the end of the rod 31 in the said part. The outer end of the bolt 32 is threaded and on the same is located a thumb-nut 32^a which, in combination with the parts just described, serves as a means for adjustably clamping the rod 31 to the part 35.

The free end of the connecting part 35 is in a usual way adjustably connected in a way 37 formed in the oscillating segment 38 lever F, which latter is of the usual construction, suitably pivoted in the usual bearing and oscillated by usual means from the movement of a usual switch cam 38 which is secured on the upper shaft E of the machine.

It will now be understood that when the machine is in operation the segment lever F is oscillated, and that through the connections between it and the needle bar, the needle bar is oscillated on its vertical axis, the extent of this oscillation being determined by the adjustment of the end of the part 35 toward or from the pivot of the oscillating lever F. As the needles carried by the needle bar are located eccentrically relative to the axis of the bar, when the needle bar is oscillated the needles are moved laterally in a path concentric with the axis about which the needle bar oscillates. If it is not desired to move the needle laterally, the end of the connection 35 may be adjusted over the axis of the oscillating lever F which, as is well known, in connection with machines in which such levers are used, prevents any movement being transmitted from it to the needle or needles. Under this adjustment it will be understood that the stitch forming mechanism is adapted to do plain straight away stitching, or in other words to make plain stitches in contradistinction to zigzag stitches.

The looper mechanism comprises a looper 39 provided with a beak 40, by means of which the loop of needle thread is engaged and passed around a bobbin case containing a mass of locking thread. A gear 40^a is connected with the hook 39 and a second gear 41, which is carried by the under shaft D, is in engagement with said gear 40^a. The gear 41 is twice the diameter of the gear 40^a, so it will be understood that, in the operation of the machine, the gear 41 and the looper 39 are revolved twice to each revolution of the gear 41. And as said gear 130

41 is secured on the shaft D and said shaft revolves, as is usual, once to each revolution of the needle operating shaft E, it will be understood that the looper revolves twice to each reciprocation of the needle.

The location of the looper 39 is such that its vertical axis is coincident with the vertical axis of the needle bar, and the needles carried by the needle holder, are located in front of the hook so that they reciprocate just outside of the path of the beak of the looper, so it will be understood that when the needle bar is oscillated the needle or needles carried by it are also oscillated laterally in a path that is concentric with the said vertical axis of the looper.

A needle plate b' provided with a needle slot or passage b² serves as a rest for the work and to separate it from the complementary stitch forming mechanism parts that are located below the needle plate, and the passage b² permits the needle to pass through the work and the needle plate and coöperate with the rotary hook mechanism which is located below it as has been described.

By properly timing the needle clamp and the looper, the needle or needles can be operated in any part of a circle around the axis on which the loop taker turns. This construction and arrangement of parts permits of the machine being very readily changed from a right to a left handed machine or vice versa or in the work being moved in any direction and the stitch-forming mechanism being adjusted so that the needles will move laterally at right angles to the movement of the said work or in any direction laterally with respect to the movement of the work. The securing of these and other valuable functions, before mentioned, is made possible by the construction and relative relation of the parts of my improved stitch-forming mechanism, and the plurality movement of the looper in the same.

Having now described a preferred form of my invention, what I claim as new is:

1. A sewing machine comprising a vertically reciprocating needle, a looper adapted to coöperate with said needle, means for moving the needle laterally relative to the looper, and means comprising a cam adapted to vary the depth of thrust of said needle vertically and thereby maintain the vertical relation between the eye of the needle and the beak of the hook.

2. In combination in a sewing machine, a stitch forming mechanism comprising a reciprocating needle-bar or holder mounted in fixed bearings and adapted to turn therein on its vertical axis, means whereby when the said needle-bar is turned on its vertical axis the reciprocating position of the needle is changed vertically and means for turning the said needle-bar on its vertical axis.

3. In a sewing machine, a stitch forming mechanism comprising a reciprocating needle-bar mounted and adapted to turn on its vertical axis, a needle carried by the said needle-bar and eccentrically with respect to the vertical axis of the same, means whereby when the said needle-bar is turned on its vertical axis the reciprocating position of the needle is changed vertically, means for turning the said needle-bar on its vertical axis, and a looper operated to coact with the said needle.

4. In a sewing machine, a stitch forming mechanism comprising a needle, means for reciprocating the said needle, means for swinging the said needle laterally, a cam operated by and during the movement of the means for laterally moving the needle, means intermediate the said needle and the cam whereby the reciprocating position of the needle is changed vertically, and a complementary stitch forming mechanism adapted to co-act with the said needle.

5. In a sewing-machine, a stitch-forming mechanism comprising a reciprocating needle-bar adapted to be oscillated on its vertical axis, means for oscillating the said needle-bar comprising an arm attached to the same, a lever 28 suitably pivoted to be oscillated, a rod 18 attached to the said arm and adapted to reciprocate in the said lever, and means for oscillating the lever.

6. A sewing-machine comprising a needle-plate, a vertically reciprocating needle located above said needle-plate, a looper located below said needle-plate, means for revolving said looper a plurality of times to each thrust of said needle, and means for moving the needle laterally relative to the looper and in a path that is concentric with the axis of the looper.

7. In combination in a sewing machine, a needle-bar, a needle carried thereby, means for reciprocating the said needle, means for swinging the said needle laterally in a path concentric with the vertical axis of the needle-bar, a complementary stitch forming mechanism comprising a hook adapted to be rotated the axis of the bar and hook being co-incident, and means for rotating the said hook a plurality of times with respect to a reciprocating movement of the needle.

8. In combination in a sewing machine, a needle-bar, a needle carried thereby, means for reciprocating the said needle, means for swinging the said needle laterally in a path that is concentric with the vertical axis of the needle-bar, a complementary stitch-forming mechanism comprising a hook adapted to be rotated the axis of the bar and hook being co-incident and means for rotating the said hook a plurality of times with respect to a reciprocating and lateral movement of the needle.

9. A stitch-forming mechanism comprising

ing a reciprocating and vibrating needle-bar, means for reciprocating said bar, and means for vibrating said bar, including a rod connected to the bar, and a lever having a tubular portion in which said rod reciprocates and a fulcrum that is coincident with the longitudinal axis of the needle-bar.

10. A stitch-forming mechanism comprising a reciprocating and vibrating needle-bar, and mechanism for actuating said bar including means for shifting the vertical working position of the bar during the vibrations thereof, said means including a cam which is attached to the bar, and a part 15 adapted to engage with said cam.

11. A stitch-forming mechanism comprising a reciprocating and vibrating needle-bar, and mechanism for actuating said bar including means for shifting the vertical 20 working position of the bar during the vibrations thereof, said means including a cam which is carried by the needle-bar, a second cam in engagement with said first cam by means of which the bar is reciprocated, and 25 its reciprocating position changed when the bar is turned on its longitudinal axis.

12. A sewing machine having a vertically

reciprocating and laterally vibrating needle, and a looper, the eye of the needle and the hook of the looper having a certain relation 30 in their first coöperative position, in combination with means whereby the vertical working position of the needle is either raised or lowered accordingly as the lateral position of the needle is changed from one 35 to the other side of the first coöperative position.

13. A sewing machine comprising a looper which revolves in a horizontal plane, a needle adapted to reciprocate in the line of 40 feed in front of said looper, means for reciprocating said needle once to a plurality of rotations of said looper, and means for oscillating said needle laterally in a path substantially parallel to the periphery of the 45 looper.

Signed at New York in the county of New York and State of New York this 6th day of Feb. A. D. 1902.
